[57] CLAIM

The ornamental design for a stud gun end, as shown and described.

DESCRIPTION

FIG. 1 is a perspective view of my stud gun end showing the stud gun with which it is associated in phantom line;

FIG. 2 is an enlarged view of my design shown in FIG. 1;

FIG. 3 is a front view thereof;

FIG. 4 is a rear view thereof;

FIG. 5 is a left side elevational view thereof;

FIG. 6 is a right side elevational view thereof;

FIG. 7 is a top view thereof; and,

FIG. 8 is a bottom view thereof.
